Attorney

UNITED STATES PATENT OFFICE.

GEORGE BROOKS, OF HAVERHILL, MASSACHUSETTS.

DESIGN FOR A TRAY.

SPECIFICATION forming part of Design No. 24,656, dated September 3, 1895.

Application filed October 8, 1894. Serial No. 525,298. Term of patent 3½ years.

To all whom it may concern:

Be it known that I, GEORGE BROOKS, a citizen of the United States, residing at Haverhill, in the county of Essex, State of Massachusetts, have invented and produced a new and original Design for Trays, of which the following is a specification.

Reference is to be had to the accompanying drawing, which fully illustrates my design.

In said drawing, the numeral 2 indicates a tray having my design within its bottom.

The leading feature of the design is a country landscape comprising as its principal elements a farm-house, a small bridge, and a quantity of shrubbery and trees. In the background, near the center of the design, appears the house 4 of old-fashioned architecture.

On its left, as shown in the drawing, is a mass of thick foliage 5, and on the extreme left, in the foreground, is shown a group of trees 6. 20 In the center of the foreground appears the bridge 7, over which a road 8 passes and continues into the distance at the extreme right of the background. Between the road and the house 4 are shown a wall 9 and a number 25 of small trees, together with two larger and more conspicuous trees 10 11.

What I claim is—

The design for a tray, substantially as shown and described.

GEORGE BROOKS.
